TENSIONING MECHANISM FOR PRINTING PRESSES

Daniel Belcher, Minneapolis, Minn., assignor to Bemis Bro. Bag Co., Minneapolis, Minn., a corporation of Missouri

Application April 10, 1933, Serial No. 665,304

13 Claims. (Cl. 101—228)

This invention relates to an improved tensioning mechanism adapted for use in connection with rotary printing presses, and is an improvement over the form shown in my patent, No. 1,653,199, issued December 20, 1927.

In printing presses of the rotary type comprising a printing cylinder and an impression or blanket cylinder, between which cylinder the web is fed to receive an impression, difficulty is sometimes experienced in the handling of the web before and after passing between said cylinders in order to relieve it of unnecessary tensional strains, which may be imparted thereto, as a result of improper tensioning of the web. In order to vary the spacing between impressions, the web is intermittently fed between the printing and impression cylinders, and the traveling speed of the web between said cylinders is relatively higher than the speed at which it travels when delivered to the machine and discharged therefrom. Because of this differential in the traveling speed of the web, means must be provided for automatically taking up slack or tensioning the web portions between the feed rolls of the machine and the printing and impression cylinders, so that the web portions between said feed rolls and printing and impression cylinders will always be kept taut, regardless of the feeding of the new web into the machine and the feeding of the printed web therefrom. In printing presses of the character above described, the web is intermittently fed between the printing and impression cylinders, and its movement may be completely interrupted at times between impressions, even though the unprinted web is being constantly fed into the machine, and the printed web discharged therefrom at the same speed. It will thus be understood that means must be provided for taking up the slack in the web between the points where it is fed into the machine and discharged therefrom, so as to maintain the web under tension at all times.

The novel tensioning mechanism herein disclosed is particularly designed for use in connection with offset printing presses, and is capable of maintaining the web at the proper tension so that the web may be fed between the printing and impression cylinders at a high rate of speed without danger of breaking the web, and whereby the impressions may be uniformly spaced upon the web.

An object of the invention is to provide an improved web tensioning mechanism particularly adapted for use in connection with printing presses employed for printing or making impressions on a

web of material, either paper or cloth, before such material is made into sacks or bags, for various purposes, having means whereby the distance between the impressions may be varied to a predetermined degree, said distance depending upon 60 the size of the bag or sack to be manufactured from the web of material.

Objects of the invention reside in the specific construction of the means provided for tensioning the web portions entering and leaving the printing and impression cylinders; in the means for relieving the web of severe tensional strains when the impression cylinder contacts with the printing cylinder to initially start the feeding action of the web between said cylinders; in the specific 70 construction and mounting of the tension rollers whereby said rollers will oscillate about a common axis, and in opposite directions, so that as the unprinted new web is being fed into the machine, the slack therein will be taken up by one of said 75 rollers, while the other of said rollers will be moving in the opposite direction to permit the printed web portion to discharge from the machine at the same speed as the unprinted web is being fed thereto; in the specific construction 80 of the means for initially setting the tension rollers into motion at substantially the instant that the blanket on the impression cylinder contacts with the web to feed it between the printing and impression cylinders, to thereby relieve the 85 web of excessive tensional strains; and, in the simple and inexpensive construction of the mechanism as a whole, whereby it may be manufactured at a minimum cost and may be readily applied to printing presses of ordinary construction 90 now in general use, without materially changing the construction of said presses.

Other objects of the invention will appear from the following description and accompanying drawings and will be pointed out in the annexed 95 claims.

In the accompanying drawings, there has been disclosed a structure designed to carry out the various objects of the invention, but it is to be understood that the invention is not confined to 100 the exact features shown as various changes may be made within the scope of the claims which follow.

In the drawings:

Figure 1 is a longitudinal sectional view of a 105 conventional printing press with some of the parts omitted and showing the invention applied thereto;

Figure 2 is an enlarged detail view showing the tensioning mechanism in normal position; 110

Figure 3 is a longitudinal sectional view showing the tensioning mechanism in operative position;

Figure 4 is a cross-sectional view on the line 5 4—4 of Figure 3;

Figure 5 is an enlarged detail sectional view on the line 5—5 of Figure 2; and

Figure 6 is an enlarged detail sectional view on the line 6—6 of Figure 2.

- 10 In the selected embodiment of the invention here shown, for purposes of disclosure, there is illustrated in Figure 1, a portion of a conventional printing press of the offset type, comprising the usual main frame 5 having an impression cylinder 6 suitably mounted thereon and the usual complementary printing rolls 7 which are adapted to receive supplies of ink from suitable inking rollers, not shown. The impression cylinder 6 is shown provided with suitable printing surfaces 15 or blankets 8 suitably secured to the periphery thereof, and which are adapted to peripherally engage a printing cylinder 9, shown mounted in suitable bearings 11 supported in brackets 12 on the main frame 5.
- 20 At the opposite end of the machine, there is shown the usual feed roll 13, which cooperates with a relatively smaller feed roll 14 to feed the unprinted web 15 to the printing and impression cylinders 9 and 6, respectively, as will be understood by reference to Figure 1. The unprinted web is supplied to the machine frame in a roll 16 supported upon a suitable spindle 17 mounted upon a frame extension 18. From the roll 16, the web passes around suitable idler rollers 19 and 25, as shown. The printed portion of the web is guided around the feed roll 13 by suitable rollers 22 and 23, and over an idler 24 from whence it is wound into a roll 25 supported upon a suitable spindle 26 also mounted upon the frame extension 18. Suitable means, not shown, is provided for driving the spindle 26 to wind the web thereon.

The novel means herein disclosed for automatically tensioning the web portions entering and leaving the printing and impression cylinders, is shown comprising a pair of anti-friction rollers 27 and 28, preferably constructed of a relatively light weight material such as aluminum. The rollers 27 and 28 are rotatably supported in a pair of arms 29 by suitable anti-friction bearings 31 mounted upon suitable studs 32 secured to the arms 29. The arms 29 have their intermediate portions secured together by a tubular connecting member 33 having flanged sleeve members 34 suitably secured to the ends thereof which, in turn, are secured to the arms 29 by bolts 30, as shown. Anti-friction bearings 35 support the tubular cross member 33 and arms 29, and are supported upon suitable pivot studs 36, secured 40 by caps 41 to the upper rails 38 of the intermediate frame section 39. The arms 29 and cross member 33 are thus secured together for operation as a unit, and cooperate to provide a common support for the rollers 27 and 28, which support 45 will hereinafter be referred to by the numeral 37.

From the feed rolls 13 and 14, the unprinted web passes downwardly under an idler 42, then forwardly around another idler roller 43, and thence rearwardly around the lower roller 28 of 50 the support 37, from whence it is guided between the impression and printing cylinders 6 and 9, respectively, by a suitable roller 44. This roller is shown provided with a brake device comprising a pair of friction elements 45 and 46 pivoted 55 to the main frame at 47, and having their opposite

ends suitably connected together by an adjusting screw 48 and a wing nut 49. A compression spring 51 is coiled about the screw 48 between the element 46 and wing nut 49, to frictionally hold the brake elements in engagement with a cylindrical extension 52 provided at one end of the roller 43, whereby the rotation of said roller may be retarded or entirely interrupted, if desired.

From the impression and printing cylinders, the printed web passes over a fixed guide 53, thence rearwardly over the upper roller 27 of the support 37, and forwardly around a relatively larger roller 54, having its periphery provided with suitable corrugations. From the roller 54, the web passes beneath the guide roller 22 and around 60 the feed roll 13, as shown.

An important feature of the invention resides in the mounting of the support 37 whereby the tension rollers 27 and 28 are mounted for swinging movement about an axis disposed between 65 said rollers. One end of a spring 55 is operatively connected to the support 37 by means of an arm 56 secured to one of the arms 29 by suitable bolts 30, which secure said arm to the adjacent sleeve member 34, as shown in Figures 2 70 and 4. The opposite end of the spring is attached to the frame 39 whereby said spring normally holds the support 37 in the position shown in Figures 1 and 2, wherein the lower portions of the arms 29 of the support are engaged with 75 suitable stops 58, carried by arms 59 secured to a rock shaft 61 journaled in suitable bearings 62 and 63, secured to the side frame members 39. The stops 58 are preferably provided with suitable yieldable elements 64 such as rubber, to 80 cushion the impact of the arms 29 therewith.

The oscillatory movement of the arms 59 is limited in one direction by suitable stops 65, secured to the main frame and provided with suitable cushion elements 66. When the support 37 90 is in its normal position, as shown in Figures 1 and 2, the arms 59 will be engaged with the stops 65, as clearly illustrated in Figures 1 and 2.

The movement of the arms 59 is limited in the opposite direction by a suitable stop 67 provided 95 on one of the frame members 39 and adapted to be engaged by an adjusting screw 68 carried by an extension 69 on the hub of an arm 70.

A brake drum 71 is secured to one end of the shaft 61 and has a brake band 72 frictionally 100 engaging the periphery thereof, one end of which is anchored to the bearing bracket 62 as indicated at 73. The opposite end of the brake band has a rod 74 secured thereto, which is received in a bracket 75 secured to one of the frame members 105 39. A suitable compression spring 76 is coiled about the rod 74 between the bracket 75 and a nut 77, received in threaded engagement with the end of the rod, as shown in Figures 2 and 4. The nut 77 and spring 76 provide means whereby 110 the frictional engagement of the brake band with the drum may be varied, as desired. The brake band functions to retard the rocking movement of the shaft 61, as will subsequently be described.

Means is provided for moving the arms 59 from 115 the positions shown in Figure 2 to that shown in Figure 3, and comprises a connecting rod 78 having one end pivotally connected to the arm 70 secured to the rock shaft 61, and having its opposite end slidably supported in a guide 81 in 120 the lower end of a cam arm 82, the upper end of which is pivotally supported upon the bracket 12 by a pivot 83. The rod 78 extends through the guide 81 and has a suitable compression spring 84 coiled thereabout, one end of which engages the 125 130

guide 81 and its opposite end a washer 85 seated against a nut 86 which is adjustably mounted upon the threaded end portion 87 of the rod, whereby the tension in the spring 84 may be varied. A suitable roller 88 is mounted on the arm 82 and engages the periphery of a cam 89 having a high point 91 adapted to engage the roller 88 and move the arm 82 in a direction towards the right, when viewed as shown in Figures 2 and 3, to the position shown in Figure 3. When the cam arm 82 is thus actuated, the arms 59 on the rock shaft 61 will be moved forwardly in a direction towards the oscillating arms 29, until the adjusting screws 68 engage the stops 67, in which position they will be temporarily retained by the brake 71—72. The purpose of thus actuating the arms 59 is to initially set into motion the support 37 for the tension rollers 27 and 28 so that the roller 28 will temporarily release the tension in the loop 92 of the web to permit the feeding movement of the web to be started between the printing and impression cylinders without imparting an excessive strain to the web.

In the operation of feeding the web between the printing and impression cylinders, it is to be understood that the web is fed between said cylinders only when the blanket 8 contacts with the web. The printing and impression cylinders rotate continuously and have the same peripheral speed, but no feeding action is imparted to the web when the blanket 8 is out of contact therewith, as shown in Figures 1 and 3, which results in the web being fed between the cylinders intermittently. It is further to be understood that the web is fed between the printing and impression cylinders at a relatively greater speed than the web is fed into and out of the machine by the feed rolls 13 and 14, which makes it necessary to provide means for compensating for the differential in speeds of the web travel. When the leading edge 60 of one of the blankets 8 engages the web, the latter is fed between the printing and impression cylinders, whereby the loop 92 formed in the unprinted web portion will shorten, as shown in Figure 3, as a result of the web being fed between the printing and impression cylinders at a greater speed than it is delivered to the machine, and such feeding action of the web will cause the support 37 to swing from its normal position, shown in Figure 2, to a position such as shown in Figure 3 against the tension of the spring 55. Such action of the support 37 will cause the loop 93 formed in the printed portion of the web to elongate as a result of the swinging action of the upper tension roller 27, whereby the tension applied to the upper and lower portions of the web will compensate for the increased speed of the web as it is fed between the printing and impression cylinders.

As soon as the blanket moves out of feeding contact with the web, the arms 29 of the support 37 will be returned to their normal positions against the stops 64 by the action of the spring 55, as a result of the feeding of the web between the printing and impression cylinders being temporarily interrupted. During such return movement of the arms 29, the traveling movement of the web portion 94 between the friction roller 44 and the fixed guide 53 may be substantially interrupted. When a blanket again engages the web portion 94, the web will again be fed between the printing and impression cylinders to be printed upon. The high

point 91 of the cam is so timed with respect to the leading edges 60 of the blankets, that the cam will engage the roller 88 of the arm 82 at substantially the same time that each blanket moves into feeding engagement with the web portion 94, to intermittently feed it between the printing and impression cylinders. Such engagement of the cam with the roller 88 will impart an initial thrust or movement to the arms 29 of the support 37, so that at the instant that one of the blankets engages and picks up the web and feeds it between the cylinders, the shortening of the loop 92 of the unprinted portion of the web will cause the arms 29 to continue to oscillate from their normal positions to that shown in Figure 3, or until the blanket moves out of contact with the web, whereupon the arms are immediately returned to their normal positions by the spring 55.

Stop means are provided on the intermediate frame section 39 for limiting the oscillation of the lower portion of the support 37 in a direction towards the printing and impression cylinders. Two such stop means are provided, one on each side of the machine, and as they are alike in construction, but one will be described in detail. Each stop means comprises a spring-actuated stop, generally indicated by the numeral 95, comprising a head 96 having a rod 97 slidably mounted in suitable guides 98 and 99 provided upon a member 101 adjustably mounted in a bracket 102 secured to the upper and lower rails of the side frame members 39. A collar 103 is secured to the rod 97 and is engaged with one end of a spring 104, the opposite end of which is seated against the guide 99, as best shown in Figure 3. The spring 104 constantly urges the stop 95 in a direction towards the support 37. A suitable resilient element 105 is seated in the head 96 to cushion the impact of the lower portion 37 with said stops.

The member 101 of the stop 95 has a stud 106 secured thereto, which is movable in an arcuately formed slot 107 provided in the bracket 102. A suitable nut 108 is received in threaded engagement with the end of the stud 106, whereby the member 101 may be secured to the bracket 102 in adjusted position.

A relatively longer stud 109 is also secured to the member 101 and, like the stud 106, traverses the slot 107 in the bracket 102. A pinion 111 is shown rotatably mounted upon the stud 109 and has an operating handle 112 secured to the hub thereof by such means as a set screw 113. A suitable nut or collar 114 is received in threaded engagement with the outer end of the stud 109 to retain the pinion 111 thereon. The pinion meshes with a gear segment 115 secured to the bracket 102, whereby the stop member 101 may be relatively adjusted upon the bracket, when the nut 108 is loosened, to thereby relatively adjust the position of the stop member 101 upon said bracket.

The position of the stop members 101 upon the brackets 102 are determined by the effective lengths of the transfer blankets secured to the periphery of the impression cylinder 6. In other words, if the blankets are comparatively short, the stop members 101 may be positioned as shown in Figure 3, and when the blankets are relatively longer, as when a larger impression is to be made upon the web, the stop members 101 may be moved upwardly in the arcuate slots 107, in a direction towards the printing cylinder 9, whereby the oscillatory movement of the lower portion 150

of the support 37 will be greater. The stops 95 are so adjusted that the lower portions of the arms 29 of the support 37 will engage the heads 96 of said stops each time a blanket moves out of contact with the printing cylinder 9. It will thus be seen that during the printing operation, when the web portions 94 is being fed between the printing and impression cylinders at a relatively higher speed than the web is being fed 10 into the machine, the rollers 27 and 28 will be oscillated about the axis of the support 37, the lower tension roller 28 moving in a direction towards the printing cylinder, and the upper tension roller 27 moving in the opposite direction. 15 Because of the roller 27 moving in a direction away from the printing cylinder 9, during the printing operation, the slack which tends to form in the web portion constituting the loop 93 will be taken up by said tension roller. At the same 20 time, the web portion forming the lower loop 92 will be kept taut by the action of the roller 28 at the lower portion of the support 37, as will readily be noted by reference to Figures 2 and 3.

Operation

25 In the operation of this novel web tensioning mechanism, the unprinted web is threaded between the feed rolls 13 and 14, and around the complementary guide rollers 42 and 43 in the usual 30 manner, and it is then looped around the lower tension roller 28 of the support 37, and thence around the friction roller 44 and between the printing and impression cylinders, as shown in Figure 3. The web is then passed over the fixed 35 guide 53 and around the upper tension roller 27 of the support 37, thence around the rollers 54 and 22, and over the feed roll 13. When the web is initially threaded through the machine, the support 37 will be in the position shown in Figure 40 1, against the stops 58. It is to be noted that when the support 37 is in normal position, as shown in Figure 1, the arms 59 supporting the stops 58 will be engaged with the fixed limit stops 65, as shown in Figures 1 and 2. The 45 movable stops 95 are then adjusted upon the brackets 102 according to the effective lengths of the transfer blankets to be used, so that the lower ends of the arms 29 of the support 37 will engage the stops 96, when the tail end 116 of each blanket 50 moves out of feeding contact with the web portion 94, as shown in Figure 3. The machine is then ready for operation, and each time a transfer blanket moves into feeding contact with the web portion 94 engaged with the periphery of the 55 printing cylinder 9, the arm 82 will be actuated by the cam 91 to initially set the support 37 into motion to advance the tension roller 28 in a direction towards the printing cylinder 9, said initial starting of the support 37 being caused by 60 the thrust exerted thereagainst by the stop 58, as a result of the rod 78 being actuated by the arm 82 and cam 91. As hereinbefore stated, the cam 91 is so timed with respect to the leading edges of the transfer blankets, that the arm 82 65 will be actuated just before each blanket moves into feeding contact with web 94 so that the tension in the web portion forming the loop 92 will be temporarily released just before each transfer blanket engages the web to feed it between the 70 printing and impression cylinders. The thrust imparted to the lower portions of the arms 29 of the support 37 by the forward movement of the stops 58, is such that the web portion forming the loop 92 will tighten around the tension roller 75 28 before the forward momentum imparted

thereto is interrupted, whereby the relative shortening of the loop 92 will cause the lower portion of the support 37 to continue in a forward direction until the feeding action of the web between the printing and impression cylinders ceases. As soon as the transfer blanket moves out of feeding contact with the web portion 94, the support 37 will engage the stops 95, whereupon the support 37 will be returned to its normal position by the spring 55, as shown in Figure 1. Such return movement of the support 37 results because of the interruption of the traveling movement of the web portion 94 between the cylinders 9 and 8 and further, because of the continuous feeding of the unprinted web into the machine.

80 The tensioning mechanism herein disclosed is comparatively simple in construction and is so designed that the web portion being fed through the machine is relieved of severe tensional strains, which might result in breakage of or damage to the web. The thrust imparted to the lower portions of the arms 29 of the supporting member 37 is important in that it starts the support 37 in motion immediately before the transfer blanket moves into feeding contact with the web portion 94, whereby said web portion may be readily started in motion without subjecting the web to severe tensional strains. The swinging action of the tensioning rollers 27 and 28 automatically takes up the slack in the web before and after printing, so that the web is always maintained taut. By relieving the web of excessive tensional strains at the beginning of each printing operation as herein set forth, the machine may be operated at a relatively higher speed than machines 100 of a similar character now in common use, thereby greatly increasing the output of the machine with the resultant decrease in the cost of printing the material. By changing the transfer blankets upon the impression cylinder and relatively adjusting the stops 95 of the tensioning mechanism, the machine may be quickly adapted for making large or small impressions, and the spacing between impressions may also be varied, depending upon the sizes of the bags into which 105 the web is to be manufactured.

110 I claim as my invention:

1. In combination with a printing press comprising web feeding rolls, and printing and impression cylinders adapted to print a web fed intermittently between them, of rolls for applying tension to the web before and after the printing operation, said rolls having a common spring-actuated support mounted for swinging movement between said feeding rolls and said printing and impression cylinders, and means for limiting swinging movement of the support in one direction, comprising a movable element which also is operable to set said support into motion, each time the feeding operation of the web is initially started between said printing and impression cylinders, thereby to relieve the web of excessive tensional strains, said support being actuated entirely by the pull of the web thereon, after it has been initially set into motion by said 115 limiting means.

120 2. In combination with a printing press comprising web feeding rolls, and printing and impression cylinders adapted to print a web fed therebetween, of means for applying tension to the web before and after the printing operation, said means comprising an oscillatable support having guides over which portions of the web are fed, yieldable means for constantly urging said support in a direction to tension the web, a mov- 125

- able stop with which said support is normally engaged, and means operating in timed relation to said printing and impression cylinders for intermittently actuating said stop to cause it to initially set said support into motion, each time the feeding operation of the web between said cylinders is started, after which said stop is rendered ineffective until the support is subsequently returned thereagainst at the completion of each 10 cycle of operation of said support. 3. In combination with a printing press comprising web feeding rolls, and printing and impression cylinders adapted to print a web fed intermittently therebetween, of means for applying tension to the web before and after passing between said printing and impression cylinders, said means comprising an oscillatable support having guides over which the web is fed, means for constantly urging the support in one direction, a 15 movable stop against which said support is normally engaged, and means operating in timed relation to the rotation of said printing and impression cylinders for intermittently actuating said stop, whereby it will thrust said support forwardly each time said cylinders move into feeding engagement with the web, thereby to relieve the web of excessive tensional strains at the beginning of each printing operation. 4. In combination with a printing press comprising web feeding rolls, and printing and impression cylinders adapted to print a web fed therebetween, of means for applying tension to the web portions entering and leaving said printing and impression cylinders, said means comprising guides over which the web is fed, an oscillatable support common to said guides, means for constantly urging said support in one direction, and a movable stop against which said support is normally engaged, said movable stop comprising a pivoted arm having a friction device associated therewith for preventing rebounding of said pivoted arm, when the stop thereof is suddenly impinged by said support upon return of the latter to its normal position. 5. In combination with a printing press comprising web feeding rolls, and printing and impression cylinders adapted to print a web fed therebetween, of means for taking up slack in the web before and after passing between said cylinders, said means comprising a movable support having rollers over which the web is fed, a movable stop, a spring operatively connected with said support and constantly urging it into engagement with said stop, and means for operating said stop to cause the latter to start said support in motion at about the same instant that the printing and impression cylinders move into feeding engagement with the web, thereby to relieve the web of excessive tensional strains, when the feeding operation of the web is initially started between said cylinders, said support being operated by the pull of the web thereon, after having been initially started by said stop. 6. In combination with a printing press comprising web feeding rolls, and printing and impression cylinders adapted to print a web fed therebetween, of means for simultaneously taking up slack in the web portions entering and leaving said cylinders, said means comprising a movable support having rollers over which the web is fed, a movable stop, means constantly urging the support into engagement with said stop, and means for initially starting said support into motion to relieve the web of excessive tensional strains when the feeding operation of the web 75 is initially started between said printing and impression cylinders, said last mentioned means comprising a cam-operated arm having an operative and yieldable connection with said stop and operating in timed relation to the operation of the printing and impression cylinders. 7. In combination with a printing press comprising printing and impression cylinders adapted to print a web fed therebetween, of means for taking up slack in the web before and after passing between said cylinders, said means comprising rollers over which the web is fed, a support common to said rollers mounted for swinging movement about an axis disposed between said rollers, a movable stop, means constantly urging the support into engagement with said stop, and means associated with the printing cylinder for suddenly thrusting said stop forwardly, at the beginning of each feeding movement of the web between the printing and impression cylinders, whereby said support is initially set into motion to thereby relieve the web of excessive tensional strains, each time the feeding operation of the web is initially started between said cylinders. 8. In combination with a printing press comprising web feeding rolls, and a constantly rotating printing cylinder with which the web is peripherally engaged, and an impression cylinder having a blanket secured to the periphery thereof and adapted to contact with the web and intermittently feed it between said printing and impression cylinders, of means for applying tension to the web before and after passing between said cylinders, said means comprising a support mounted for swinging movement and having guides engaging the web, a movable stop for said support, a spring constantly urging said support into engagement with said stop, and cam-actuated means for exerting a sudden forward thrust against said stop, whereby the latter will initially set said support into motion just before the blanket moves into feeding engagement with the web, to thereby relieve the web of excessive tensional strains, each time it is initially started, said stop being rendered inoperative to further actuate said support, during completion of each feeding movement of the web between said printing and impression cylinders. 9. In combination with a printing press comprising web feeding rolls, and a constantly rotating printing cylinder with which the web is peripherally engaged, and an impression cylinder having a blanket secured to the periphery thereof and adapted to contact with the web and intermittently feed it between said printing and impression cylinders, of means for applying tension to the web prior to and following the printing operation, said means comprising a movable support having guides engaging the web, a movable stop for limiting movement of said support in one direction, yieldable means constantly urging said support into engagement with said stop, and means associated with the printing and impression cylinders for setting said support into motion before the blanket moves into feeding engagement with the web, whereby the web is relieved of excessive tensional strains at the beginning of each feeding movement between said cylinders, said support thereafter being actuated entirely by the pull of the web thereon. 10. In combination with a printing press comprising web feeding rolls, and printing and impression cylinders between which the web is intermittently fed to be printed upon, a support

- mounted for swinging movement and having a tension roller thereon engaging the web, a stop movable within predetermined limits and with which said support is normally engaged, yielding 5 means constantly urging the support into engagement with said stop, a cam-actuated arm having an operative connection with said stop and adapted to actuate the latter just before the feeding operation of the web between the printing and impression cylinders is started, whereby said stop will thrust said support forwardly at substantially the same instant that said cylinders engage the web to feed it therebetween, whereby the web is relieved of excessive tensional strains 10 each time the feeding operation thereof is initially started as a result of said cylinders moving into feeding engagement therewith, said support thereafter being operated entirely by the pull of the web thereon.
- 15 11. In combination with a printing press comprising web feeding rolls, and printing and impression cylinders between which the web is intermittently fed to be printed upon, rollers for applying tension to different runs of the web, a swingable support for said tension rollers, stops for limiting the swinging movement of said support, one of said stops being adjustable to vary the movement of the support, and the other of said stops being movable within predetermined limits, 20 means constantly urging the support into engagement with said movable stop, a friction device associated with said movable stop for retarding its movement, and a cam-device associated with said printing and impression cylinders and having an operative connection with said movable stop and adapted to operate it in a direction to set said swingable support into motion, just before the blanket on the impression cylinder moves into feeding engagement with the web, whereby the 25 latter is relieved of excessive tensional strains each time it is fed between the printing and impression cylinders.
- 30 12. In combination with a printing press comprising web feeding rolls and printing and impression cylinders adapted to print a web fed therebetween, of means for applying tension to the web portions entering and leaving said print- 35

- ing and impression cylinders, said means comprising guides over which the web is fed, an oscillatable support common to said guides, means for constantly urging said support in one direction, a movable stop against which said support is normally engaged between printing operations, a cam-actuated arm associated with the printing cylinder, means operatively connecting said arm with said movable stop and adapted to thrust said stop forwardly each time the printing and impression cylinders move into feeding engagement with the web, whereby said support is initially set into motion by said stop to thereby relieve the web of excessive tensional strains, each time said cylinders move into printing and feeding engagement therewith, the movement of said support thereafter being completed by the pull of the web thereon, and a friction device for retarding the return movement of said movable stop.
13. In combination with a printing press comprising web feeding rolls and printing and impression cylinders adapted to print a web fed therebetween, of means for applying tension to the web portions entering and leaving said printing and impression cylinders, said means comprising guides over which the web is fed, an oscillatable support common to said guides, means for constantly urging said support in one direction, a movable stop against which said support is normally engaged between printing operations, a cam-actuated arm operating in timed relation to the printing cylinder and having an operative connection with said movable stop, said cam-actuated arm operating said stop to cause the latter to intermittently thrust said support forwardly at substantially the same instant that the printing and impression cylinders move into feeding engagement with the web, whereby said support is initially set into motion by said stop to thereby relieve the web of excessive tensional strains, each time said cylinders move into printing and feeding engagement therewith, and a friction device for retarding the return movement of said movable stop, when it is subsequently engaged by said support.

DANIEL BELCHER.
